UNITED STATES PATENT OFFICE.

ARTHUR A. MERRITT, OF WORCESTER, MASSACHUSETTS, ASSIGNOR TO WILLCOX & GIBBS SEWING MACHINE COMPANY, OF NEW YORK, N. Y., A CORPORATION OF NEW YORK.

THREAD-GUIDE.

1,044,068.

Specification of Letters Patent. Patented Nov. 12, 1912.

Original application filed December 12, 1908, Serial No. 467,163. Divided and this application filed January 12, 1910, Serial No. 537,682. Renewed September 12, 1912. Serial No. 720,053.

To all whom it may concern:

Be it known that I, ARTHUR A. MERRITT, of Worcester, Massachusetts, have invented a new and useful Improvement in Thread-Guides, which invention is fully set forth in the following specification.

This is a division of my application filed December 12th, 1908; Serial No. 467,163, for improvements in sewing machines.

10 The present invention, which relates to improvements in thread-guides, will be readily understood by reference to the illustration in the accompanying drawing of what is at present regarded as the preferred 15 embodiment thereof.

In said drawing, Figure 1 is a longitudinal sectional view; and Fig. 2 is a similar view with the parts spread out.

11 is a part of the frame-work of a sewing 20 machine or other support to which the thread-guide is adapted to be attached. A cup-like part 1 and a stem 2 are both fixed to the part 11 by a set-screw 3. A head 4 at the outer end of stem 2 has therethrough 25 a thread-eye 5 into which thread may be introduced through a slot 6 opening into one side of said eye. A tubular plunger or sleeve 7 surrounds the stem 2, and is adapted to have longitudinal sliding movement in the cup-like part 1 and on stem 2. A spring 8 coiled 30 about the stem 2 normally presses the tubular plunger outward until a shoulder 9 about the interior of its outer end bears against a shoulder formed about the stem by the inner 35 side of head 4, causing the outer end of the plunger to encircle the inner end of the head, so as to extend over and close the slot 6, thereby preventing disengagement of the thread from the eye 5 when the parts are in 40 this position. To introduce thread into the eye 5, the operator grips the milled portion 10 of the plunger and presses the latter inward against the tension of spring 8, uncovering the slot 6 so that thread may be passed 45 therethrough into the eye.

What is claimed is:—

1. A thread-guide consisting of a stem

having thereon a shoulder and having therethrough a thread-eye and a slot leading into said eye, and a sleeve movable on said stem to a position, determined by contact with the shoulder, to extend across said slot and to close the same, or to a position clear of said slot to open the same.

2. A thread-guide consisting of a stem having a slotted thread-eye therethrough, a part movable along said stem to close and open the slot of the eye, and a spring normally pressing said part to position to close said slot.

3. A thread-guide consisting of a stem having a slotted thread-eye therethrough, a sleeve movable along said stem to close and open the slot of the eye, and a spring normally pressing said sleeve to position to close said slot.

4. A thread-guide consisting of a stem having at one end a head with a slotted thread-eye therethrough, a sleeve movable along said stem to close and open the slot of the eye, and a spring normally pressing said sleeve against the head of the stem to close said slot.

5. A thread-guide consisting of a fixed cup-like part, a fixed stem passing through said cup-like part and having a slotted thread-eye at its outer end, a sleeve movable along said stem to close and open the slot of the thread-eye the inner end of said sleeve and outer end of the cup-like part forming a sliding telescopic joint, and a spring about the stem within the cup-like part and the sleeve normally pressing the latter to position to close the slot of the thread-eye.

In testimony whereof I have signed this specification in the presence of two subscribing witnesses.

ARTHUR A. MERRITT.
